(57) **CLAIM**

I claim the ornamental design for a pet dish stand, as shown and described.

DESCRIPTION

The pet dish stand is comprised of three parts, which are attached together to form the stand. The pet dish stand can be used to support bowls, trays, and/or any other items. Those bowls, trays, or items could contain food and/or water for a pet. In fact, the pet dish stand can also be used as a stand to store a pet's toys. Those toys could be placed directly on the stand or on a tray, in a container, and/or in other storage devices, which are positioned on the stand.

FIG. 1 is a perspective view of the pet dish stand showing the front, side, and top.

FIG. 2 is a perspective view of the pet dish stand shown disassembled.

FIG. 3 is another perspective view of the pet dish stand shown in use.

FIG. 4 is a side view of the pet dish stand.

FIG. 5 is the other side view of the pet dish stand.

FIG. 6 is a top view of the pet dish stand; and,

FIG. 7 is a bottom view of the pet dish stand.

The broken lines in FIGS. 3, 4, 5, 6, and 7 displaying bowls are for illustrative purposes only and form no part of the claimed design.
